IGNITION TIMER

Marion Mallory, Detroit, Mich.

Original application January 4, 1937, Serial No. 119,006. Divided and this application October 4, 1940, Serial No. 359,771

5 Claims. (Cl. 200—31)

This invention relates to ignition timers for internal combustion engines and more especially to the automatic control thereof in accordance with the speed and load. This application is a division of application Serial No. 119,006, filed January 4, 1937, abandoned March 1, 1941.

For smooth idling, an extreme retardation of the timing is necessary, but upon a slight opening of the throttle, there should be an appreciable immediate advance of the timing. Following this, there should be a further gradual advance as the speed increases, but when the engine is working under full load with wide open throttle at either low or high speeds, it is desirable to retard the advance to some extent to prevent detonation.

It has heretofore been proposed to use centrifugal means to advance the spark in proportion to the speed, and supplemental spark advancing means controlled by the suction of the engine intake. In the operation of devices of this kind as heretofore proposed however, either the suction is not immediately effective to advance the spark as soon as the throttle starts to open, or it is not rendered ineffective when the throttle is wide open.

With the above facts in mind, it is an object of the present invention to provide, in addition to a centrifugal spark advance, a supplemental suction controlled spark advancing means and means in the nature of a suction controlled valve to render the suction controlled spark advancing means effective at the proper time. This supplemental spark advancing means is connected into the intake manifold but is cut off therefrom at the proper time by the valve, which is connected to the intake on the atmospheric side of the throttle valve when the latter is closed for idling. As soon as the throttle starts to open, the suction controlled valve is subjected to suction from the inflowing fuel and, since it is normally held closed by a light spring, it will immediately open, thus subjecting the spark control to the action of the high vacuum of the manifold, which advances the spark. With the throttle wide open at either high or low speeds, the suction may be high enough to operate the suction controlled spark advance. However, the suction in the intake passageway will be insufficient to open the valve to permit the vacuum spark control to advance the spark.

It is also an object of the invention to provide convenient means to easily adjust the maximum range of speed governor advance, the rate of such advance, and the maximum range of suction controlled advance, so that these characteristics of

the spark timing may be properly set for the individual timer or the individual engine with which the timer is used.

5 The above and other objects and advantages of the invention will be more particularly explained in connection with the accompanying drawings, in which

Fig. 1 is a horizontal section through the timer housing above the brake plate, showing the suction controlled valve in a position to cut off the vacuum between the brake and the manifold, allowing the brake to engage and hold the timer in a retard position.

10 Fig. 2 is a sectional view showing the suction control valve of Fig. 1 in a position to connect the brake with the intake manifold vacuum for advancing the spark.

Fig. 3 is a vertical section through the timer housing, the circuit breakers and springs being omitted.

15 Fig. 4 is a plan view of the circuit breakers and plate.

Fig. 5 is a section taken on the line 5—5 of Fig. 3.

20 Fig. 6 is a section taken on the line 6—6 of Fig. 3.

Fig. 7 and 8 are charts representing the governor curves resulting from various adjustments of the timer.

25 30 As illustrated in Figs. 1, 2 and 3, the invention is associated with an engine intake manifold 10 having a fuel intake passageway 11 with a throttle valve 12 therein. The housing 23 is formed with a shank 33 which is lined with a bushing 34 to provide a bearing for the timer shaft 35 adapted to be driven from the engine. The shaft 35 has a reduced extension 36 on which is mounted a sleeve 37 carrying the circuit breaker cam 38. A circuit breaker plate 39 fits into the housing 23 and is secured by insulated screws 40 and 41, to which the circuit breaker springs 42 and 43 are also secured. The terminal screws 40 and 41 are electrically connected by an insulated conductor 44 and the inner ends of the springs 42 and 43, which constitute parts of the primary circuit, are secured to overlapping circuit breakers 45 and 46. Since the mountings of the latter do not constitute a part of the present invention, it is not necessary to describe the same here in detail.

35 40 45 50 The sleeve 37 is formed with a flange 56 to which a governor plate 55 is clamped by means of a clamping member 57 and screws 58. A drive plate 49 is fixed to the shaft 35. A circular brake plate 26 floats on the timer shaft 35 between the plates 49 and 55.

The plate 55 and circuit breaker cam 38 are adapted to be advanced with reference to the brake plate 26 by centrifugal governor mechanism, which may be termed the primary timing control and which will be hereinafter more particularly described.

The brake plate 26 is adapted to be held in an advanced position with reference to the drive plate 49 by a spring 52, except when it is held in retard position by the engagement of a brake 25 with its periphery. This brake is carried by a piston 24 which operates in a cylinder 22 connected to the timer housing 23. A spring 27 holds the brake in engagement with the plate 26, until there is sufficient vacuum developed in the cylinder to overcome the action of the spring, thereby retracting the piston and permitting an immediate advance of the plate 26 with a corresponding advance of the timing. This may be termed the supplemental or vacuum timing control.

The vacuum is developed in the cylinder 22 through a conduit 13 which is connected through a valve casing 14 and conduit 15 to the manifold 10. Communication between the conduits 13 and 15 is adapted to be cut off by a valve 16, which is normally held closed by a spring 17. The end of the casing beneath the valve has a passageway 18 leading into the intake 11 immediately above the throttle valve 12 when the latter is in closed or idling position. A vent 19 in the other end of the casing 14 permits the valve to be opened by suction through the passageway 18 in opposition to the spring 17. An annular groove 20 in the valve 16 is at all times in communication with the conduit 13. Another annular groove 21 bleeds into the passageway 18. Thus the valve is prevented from becoming vacuum-locked against the casing wall.

The centrifugal governor mechanism comprises two governor weights 47 and 48. One of these weights, as 48, is pivotally mounted on a pin 53 secured to the plate 26. The other weight 47 is pivotally mounted on a pin 54 which projects downwardly from the plate 55 secured to the sleeve 37. As the weights fly outwardly about their pivots 54 and 53 under the influence of centrifugal force, the edges 59 roll on each other, forcing the pivots 54 and 53 farther apart and causing an advance of the plate 55, sleeve 37 and circuit breaker cam 38 with reference to the plate 26. The extreme outward movement of the weights 47 and 48 is limited by their engagement with the pins 60 and 61 secured in the respective plates 55 and 26.

The characteristics of the spark advance curve necessary for the most economical operation vary widely in different cars and different engines, and even in the same engine at different periods of its life. This invention therefore provides for universal adjustment of these characteristics.

In order to adjustably limit the maximum advance of the governor plate 55 and cam 38 with reference to the plate 26, as controlled by the governor weights 47 and 48, an arm 68 is mounted for pivotal adjustment about the shaft 36 and is secured in its adjusted position by a clamping screw 69, which extends through a slot 70 in said arm into the plate 26. The cam edge 71 of the arm 68 is adapted to engage the downwardly projecting end of the pin 54, which extends into a slot 72 in the plate 26, and thereby progressively decreases the maximum range of advance of the plate 55 with reference to the plate 26, as the arm is adjusted toward the left. The position of the adjustment is indicated on the

scale 73 by the pointer 74 on the end of the arm 68.

The action of the governor weights 47 and 48 in advancing the plate 55 is resisted by a spring 75, which is so mounted that the point where the advance begins and the ratio of such advance to the increase in speed may be adjusted. One end of the spring 75 is connected to a pin 76 secured to an arm 77 which is mounted for adjustment about a pivot pin 78 secured to the under side of the plate. The pin 76 projects upwardly through an arcuate slot 79 in the plate and the arm 77 is secured in adjusted position by a clamping screw 80 which extends through a slot 81 into the arm. The other end of the spring 75 is connected to a pin 82 on an arm 83 which is pivotally mounted on the pin 78. An arm 84 is mounted for pivotal adjustment about a pin 85 on the plate 55 and is secured in adjusted position by a clamping screw 86, which extends through a slot 87 in said arm and into the plate 55. A pin 88 secured to the arm 84 engages an arcuate slot 89 in the arm 83.

Adjustment of the arm 84 about its pivot 85 varies the position of the pin 88 in the slot 89 and the consequent leverage of the arm 83 about its pivot 78, when the governor weights act to advance the plate 55 in opposition to the resistance of the governor spring 75 transmitted through the pin 82, arm 83, pin 88 and arm 84 to the plate 55. This adjustment therefore varies the tension of the governor spring and the ratio of the speed controlled advance of the timing as compared to the speed.

Adjustment of the arm 77 about its pivot 78 toward the outer edge of the plate 26 increases the tension on the governor spring 75.

Adjustment of the arm 68 about the shaft 36 as a center causes said arm to cover more or less of the end of the slot 72, into which the pin 54 projects, and the engagement of the pin with the edge 71 of the arm variably limits the maximum advance of the plate 55 and consequently the maximum speed controlled advance of the spark.

The brake plate 26 is held adjacent the drive plate 49 by two pins 59 and 59^a which are inserted through slots 51 and 51^a in the brake plate and secured in the drive plate. These slots therefore limit the rotational displacement of the plate 26 with reference to the plate 49. In order to adjustably limit the maximum relative advance of the plate 26, and consequently the vacuum controlled spark advance, an arm 62 is mounted for adjustment about a pivot 63 on the plate 26 and is secured in adjusted position by a clamping screw 64 which extends through a slot 65 into said plate. The inclined end 66 of the arm 62 is adapted to engage the head of the pin 59 and thereby progressively limit the effective length of the slot 51. The maximum advance of the brake plate 26, thus limited, is indicated by the point of the arm 62 on the scale 67.

In the operation of the vacuum controlled advance, the valve 16 is closed whenever the throttle valve is closed. In the structure illustrated in Fig. 1, there will be under such conditions no vacuum in the cylinder 22, the brake 25 will engage the brake plate 26, the latter will be held in retarded position, and there will be an extreme retardation of the spark. However, as soon as the throttle valve 12 is opened, perhaps for operation at about 14 miles per hour, the inflow of fuel mixture past the mouth of the passageway 18 will induce a sufficient vacuum in the latter to open the valve 16. There will at this time be a

comparatively high vacuum in the manifold 10, which will immediately cause a maximum vacuum advance of the spark. This advance may be in the neighborhood of 10° or 15°, depending upon the adjustment of the arm 62. This vacuum advance is added to the speed controlled spark advance which increases gradually through a predetermined range of speed and which is effected by advancing the circuit breaker cam with respect to the brake plate 26.

The strength of the spring 17 is so chosen that it overcomes the vacuum induced by the flow through the open intake passageway at a speed in the neighborhood, say, of 50 miles per hour. This renders the vacuum spark advancing means ineffective, so that the spark advance is then entirely dependent upon the centrifugal governor. This moderate recession from the maximum spark advance is desirable at the highest speeds to prevent detonation.

Adjustment of the arm 62 about its pivot 63 causes the end 66 of the arm to variably limit the range of movement of the brake plate 26 with reference to the plate 49, thereby adjustably limiting the possible advance of the spark when the piston 24 is retracted by the vacuum in the manifold.

From the foregoing description, it will be seen that I have provided means to advance the timing in accordance with speed throughout a predetermined adjustable range and, in addition thereto, improved vacuum controlled means to cause a predetermined spark advance upon a change from idling to low speed travel, this vacuum controlled means being ineffective for advancing the spark at the highest speeds, or when the engine is working under a heavy load with open throttle.

The timer also has all the adjustments necessary to secure the desired spark advance curve for the most satisfactory performance of any given engine, as illustrated in Figs. 7 and 8. As above stated, the desired rate of spark advance by the governor, as compared to increased speed of the engine, is obtained by variation in the tension of the governor spring 75, which is effected by adjusting the arm 84. Each graduation on the edge of the slot 89 represents a difference of approximately 400 R. P. M. on the governor advance curve. These curves for different adjustments are represented at A, B, C, D, E, F, in Fig. 7. When adjusting the governor for a smaller advance, such as 20° or less, to finish at 4000 R. P. M. or later as illustrated by governor advance curves G, H, I, J, K, L, it may be necessary to place additional tension on the governor spring 75 by adjusting the arm 77 toward the outer edge of the plate, as above explained. Curves A, B and C may be produced by using an 8-ounce governor spring. Curves D to L inclusive may be produced by using a 16-ounce governor spring.

When the engine is operating under full throttle and heavy load and the vacuum in the intake manifold drops to approximately 12" mercury or under, the spring 27 will cause the brake 25 to engage the plate 26, bringing it into retard position and effecting a like retardation of the centrifugal governor assembly and circuit breaker cam. The governor curve will then be similar to that shown at A. As the engine speed increases, or the throttle is partly closed, the vacuum in the intake manifold will build up to a point in excess of 12" mercury, at which point the piston 24 will be retracted, releasing the brake plate 26, whereupon the governor drive spring 75

52 will immediately advance the brake plate and the governor and cam assemblies. The governor will then produce a light load curve similar to that shown by the broken line A', which has for illustration been set 10° higher than the load curve A.

On some engines the initial timing is set very close to top dead center. With this setting a rapid intermediate advance of the governor is necessary from approximately 400 R. P. M. to 800 R. P. M. of the engine, as shown by curves P, Q, R, S, on Fig. 8. To produce these curves, it is necessary to use a special governor spring lever adjustment arm 84, stamped 6°, 10°, 12° 15 or 14°, indicating the point at which the slower advance of the timing begins. With this adjustment arm, a 24-ounce governor spring should be used. The normal position of the spring post 75 is in the end of the slot 79 nearest the center of the plate. In case the governor advances too fast through the lower speed range, resulting in a slight spark knock, the spring post 76 should be adjusted toward the other end of the slot.

20 While the suction control of the spark advance is shown in connection with a brake adapted to be applied to a plate that carries the timing mechanism, it will be apparent that the same suction control may be used with any other type of timing mechanism, whether the spark is advanced by moving the housing, the circuit breaker plate, circuit breaker cam, or the complete governor assembly. Various other details may also be modified without departing from the scope of the invention as defined in the appended claims.

25 I claim:

30 1. An ignition timer for an internal combustion engine comprising a rotatable timer shaft, a circuit breaker cam mounted on and driven by said shaft, said cam adapted to have a limited relative rotative movement on said shaft, centrifugal means for advancing the cam on said timer shaft, and a plate also mounted on said shaft and adapted to have a limited relative rotative movement thereon, said cam and plate 35 also adapted to have a limited relative rotative movement on said shaft with respect to each other, and means connecting said plate and cam whereby advancing said plate on said shaft effects a corresponding advance of said cam on said shaft, said centrifugal means advancing said cam on said shaft independently of said plate.

35 2. An ignition timer for an internal combustion engine comprising a rotatable timer shaft, a circuit breaker cam mounted on and driven by said shaft, said cam adapted to have a limited relative rotative movement on said shaft, centrifugal means for advancing the cam on said timer shaft, and a plate also mounted on said shaft and adapted to have a limited relative rotative movement thereon, said cam and plate 40 also adapted to have a limited relative rotative movement on said shaft with respect to each other, and means connecting said plate and cam whereby advancing said plate on said shaft effects a corresponding advance of said cam on said shaft, said centrifugal means advancing said cam on said shaft independently of said plate and independently of said below-mentioned suction controlled means, and suction controlled means for advancing said plate on said shaft.

45 3. An ignition timer for an internal combustion engine comprising a rotatable driving member, a circuit breaker member mounted on and driven by said driving member and having a limited rotative movement relative to said driv-

ing member, a plate also mounted on said driving member and having a limited rotative movement relative to said driving member, said circuit breaker member also having a limited rotative movement relative to said plate, centrifugal means for advancing the circuit breaker member on said shaft and with respect to said plate and independently of said below-mentioned suction controlled means, and suction controlled means for advancing both the said plate and the circuit breaker member as a unit on said driving member.

4. An ignition timer for an internal combustion engine comprising a rotatable timer shaft, a circuit breaker cam mounted on and driven by said timer shaft and having a limited rotative movement relative to said timer shaft, a plate also mounted on said timer shaft and having a limited rotative movement relative to said timer shaft, said circuit breaker cam also having a limited rotative movement relative to said plate, centrifugal means for advancing the circuit breaker cam on said shaft and with respect to said plate and independently of said below-mentioned suction controlled means, and suction controlled means for advancing both the said plate and the circuit breaker cam as a unit on said timer shaft.

5. An ignition timer for an internal combustion engine comprising a timer shaft, a plate rigidly connected thereto, a second plate having an ignition cam mounted thereon, the second plate being free to oscillate a limited distance on said timer shaft, a spring connected between the first and second named plates which tends to hold the second named plate to its limited movement in the direction of rotation of timer shaft, a friction brake to engage the second named plate and overcome said spring to hold the second named plate and said ignition cam to its limited movement in a direction opposite to that of said timer shaft, a governor weight pivotedly mounted on second named plate, a third plate and a cam mounted on said plate, both cam and said third plate being free to oscillate on said timer shaft, a second governor weight pivotedly mounted on the third named plate, said second governor weight engaging with the first governor weight to advance the third named plate and cam as the speed of the said timer shaft increases, and spring means connecting the second and third named plates together to resist the power of the centrifugal governor weights.

MARION MALLORY.
